(57) **CLAIM**

We claim the ornamental design for a container and lid assembly, as shown and described.

DESCRIPTION

FIG. 1 is a perspective view of a container and lid assembly according to one embodiment.

FIG. 2 is a front view of the container and lid assembly of FIG. 1.

FIG. 3 is a rear view of the container and lid assembly of FIG. 1.

FIG. 4 is a first side view of the container and lid assembly of FIG. 1.

FIG. 5 is a second side view of the container and lid assembly of FIG. 1.

FIG. 6 is a top view of the container and lid assembly of FIG. 1; and,

FIG. 7 is a bottom view of the container and lid assembly of FIG. 1.

Portions of the container and lid assembly shown in broken lines are included for the purpose of illustrating environment and form no part of the claimed design.

1 Claim, 7 Drawing Sheets
